INVENTOR
George M. Davis,
by Emory O. Whitney, his Attorney.

UNITED STATES PATENT OFFICE.

GEORGE M. DAVIS, OF HARTFORD, CONNECTICUT.

WATER-TUBE BOILER.

SPECIFICATION forming part of Letters Patent No. 640,879, dated January 9, 1900.

Application filed March 22, 1899. Serial No. 710,072. (No model.)

To all whom it may concern:

Be it known that I, GEORGE M. DAVIS, a citizen of the United States of America, and a resident of the city and county of Hartford, 5 in the State of Connecticut, have invented certain new and useful Improvements in Water-Tube Boilers, of which the following is a specification.

This invention relates to boilers of that 10 class generally known as "upright water-tube boilers," one object of the invention being primarily to furnish an improved and simplified boiler of this class embodying a furnace and to so construct and organize the parts 15 thereof as to secure the maximum amount of heating-surface to the minimum amount of space occupied by the boiler as a whole; further, to so construct and dispose the fire-box and the water or steam tubes of the boiler as 20 to facilitate a rapid generation of steam at an economic expense in fuel.

A further object of the invention is to furnish a boiler and furnace in which the boiler proper is constructed wholly of wrought-metal 25 tubing and comprises a plurality of horizontally-disposed endless tubes, a multiplicity of vertical tubes disposed substantially concentric about a common center and communicating at their upper and lower ends with 30 said endless tubes, a base supporting said vertical tubes and having an ash-pit, a grate supported within the circle described by the vertical tubes, and a so-called "porcupine" located within the circle of vertical tubes and 35 having radially-disposed tubes communicating with said vertical tubes and endless tubes.

With these objects in view my invention consists in a boiler and furnace embodying certain novel features and improved details 40 in construction and organization, as will be hereinafter fully described, and pointed out in the claims.

In the drawings accompanying and forming part of this specification, Figure 1 is a 45 side elevation, partly in section, of a water-tube boiler and furnace embodying my invention. Fig. 2 is a plan view, partly in section, of said boiler, the section being taken on a line corresponding with the dotted line 2-2, 50 Fig. 1; and Fig. 3 is a detail on an enlarged scale, partly in elevation and partly in central longitudinal section, of a portion of one

end of a vertical tube and the coupling by means of which said tube is connected to one of the horizontal endless tubes of the boiler. 55

Similar characters designate like parts in all the figures of the drawings.

In the preferred construction and organization thereof illustrated in Figs. 1 and 2 of the accompanying drawings the boiler and 60 furnace comprises, essentially, a base B, constructed, preferably, of cast metal in cylindrical form and having a suitable ash-pit 3; two concentrically and horizontally disposed cross-sectionally circular wrought-metal endless tubes located one above the other and 65 designated, respectively, by 4 and 5; an external series of vertical tubes 6, arranged side by side in close proximity, preferably in the arc of a circle about a common center and connected at opposite ends with the horizontal 70 endless tubes 4 and 5 in such manner as to facilitate a circulation of water and steam through said vertical tubes and horizontal endless tubes; an internal porcupine set of 75 tubes designated in a general way by P and embodying a central vertical tube 7, terminating in a steam-dome 8 and a series of radially and horizontally disposed branch tubes 9, some of which are closed at their 80 outer ends and others of which are connected for communication with the upper endless tube 5 and certain of the vertical tubes 6; an intermediate particircular horizontal tube 10, disposed a sufficient distance above the ring-tube 4 as to form the upper part of the firebox opening 12, and which particircular tube 85 10 communicates with the upper endless tube 5 through the medium of certain of the vertical tubes 6, which are obviously made of 90 reduced length as compared with others of said tubes 6; a fire-grate G, supported in any suitable manner within the circle described by the external series of vertical tubes 6; an external casing 13 of suitable form surrounding the external series of tubes 6 and terminating at its upper end in a smoke-pipe 13'; a supply-pipe 14, communicating with the boiler near the base thereof, and a steam-pipe 15 in communication with the steam-dome 8. All of the foregoing parts are shown 95 in the drawings and will be hereinafter more fully described.

While the boiler illustrated in the accom-

panying drawings and herein described is more particularly adapted for use as a steam-boiler, it will be obvious that the same is applicable for use as a hot-water heater, and 5 the same will in practice be constructed, elusive of the base B and external sheet-metal casing 13, wholly of wrought-metal tubes, the endless tubes 4 and 5 being bent in the arc of a circle and having their ends welded or 10 brazed together.

In practice the vertical tubes 6 will be set side by side preferably in the arc of a circle and with their adjacent faces in such close proximity as to preclude the possibility of 15 coal contained in the fire-box siftng through between said tubes.

As a convenient means of connecting the vertical tubes with the horizontal endless tubes said endless tubes are drilled and 20 tapped, as will be understood by reference to the accompanying drawings, and the opposite ends of the vertical tubes are tapped to receive couplings C and C', the ones C being screwed into the upper ends of the vertical 25 tubes 6 and the endless tube 5 and the ones C' being screwed into the lower end of the vertical tubes and the lower endless tube 4, as hereinafter more fully described.

For convenience in assembling and connecting 30 up the vertical tubes and the endless tubes I employ, preferably in connection with the lower ends of each vertical tube, an ordinary nipple-coupling C', one end of which is screwed into the lower end of the tube and 35 the other end into the tapped opening in the lower endless tube 4, said coupling or nipple having its screw-threaded ends preferably tapered to insure a water-tight joint, and I preferably employ, in connection with the 40 upper end of each tube, an improved coupling C (see Fig. 3) of a construction which will enable each vertical tube to be readily connected up with the upper endless tube independent of the other vertical tubes, which 45 is of material advantage and saves much time in the setting up or assembling of the parts of the boiler. This coupling C comprises in the preferred form from thereof (illustrated most clearly in Fig. 3) a substantially tubular 50 main body portion 16, having one end, as 17, thereof tapered externally and screw-threaded to fit a corresponding screw-threaded opening in the upper endless tube 5, and having the lower end 18 thereof straight and 55 screw-threaded to fit a corresponding screw-threaded opening in the upper end of the vertical tube 6, the threads of the opposite ends of the main body portion of the coupling being, preferably, right-hand threads and be- 60 ing separated from each other by a polygonal or nut-like portion 19, adapted to be grasped by a wrench whereby to screw the coupling outward from the upper end of the tube 6 and into the endless tube 5, the lower screw- 65 threaded end of the main body portion of the coupling C being furnished with a jam-nut 20, which will be screwed down tightly upon a

piece of packing 21, interposed between the upper end of the tube 6 and said jam-nut, whereby an impervious or steam-tight joint 70 is provided.

In connecting up the upper end of the tube 6 with the upper horizontal endless tube 5 the coupling C will be screwed down far enough into the upper end of the tube 6 as to bring 75 the upper end of the coupling slightly below said endless tube, after which the coupling C will be screwed outward until the upper tapered screw-threaded end thereof is screwed tightly into the tapered opening in said endless tube, which opening is concentric to said coupling, after which the jam-nut 20 will be screwed down until the packing 21 is tightly compressed between the same and the upper end of said tube.

The internally-disposed porcupine P, which is connected up in any suitable manner and communicates with the endless tubes and vertical tubes, may be of any desired construction and organization, it preferably consisting of the central tube before described, having a series of sets of radially and horizontally disposed short branch tubes, said sets being located one above the other and communicating with the central tube at different 95 points in the length thereof.

In practice, if desired, an asbestos packing (not shown) may be interposed between the outer series of vertical tubes 6 and the external sheet-metal casing 13 to obviate accidental overheating of said casing.

In the drawings I have shown an ordinary simple form of grate; but it will be obvious that any suitable form of fire-box and grate may be employed, and, further, in practice 105 the fire-box opening and ash-pit opening will be provided with suitable doors, which for convenience are not shown in the accompanying drawings.

By arranging the vertical tubes in close 110 proximity to each other and connecting them up with the endless tubes, as described, and as illustrated in the accompanying drawings, and providing a porcupine set of tubes and connecting this up with the ring-tubes and 115 vertical tubes I secure a greater amount of effective heating-surface than has been heretofore possible in boilers of this class of the same size and at the same time produce a boiler in which steam may be quickly generated at a minimum expense in fuel, and which 120 will withstand extreme high pressure, for the reason that all of the tubes of said boiler will, in practice, be constructed of wrought-steel.

I claim—

1. A boiler and furnace comprising a base; a horizontally-disposed wrought-metal endless tube supported on said base and having a water-supply pipe in communication therewith; a multiplicity of vertically-disposed 130 wrought-metal tubes disposed in the arc of a circle about a common center; a horizontally-disposed endless tube supported above and in concentric relation with the lower endless

tube; a series of hollow couplings adjustably connecting the upper and lower ends of the vertical tubes to the upper and lower endless tubes respectively; a steam-dome vertically disposed within the circle described by the vertical tubes; a multiplicity of radially and horizontally disposed tubes communicating with the steam-dome and vertical tubes; a steam-pipe communicating with the steam-dome; and a grate supported within the circle described by the vertical tubes.

2. A boiler and furnace comprising a base; a horizontally-disposed wrought-metal endless tube supported on said base and having a series of tapered screw-threaded openings in the upper wall thereof; a superposed endless tube having a series of tapered screw-threaded openings in the lower wall thereof, a multiplicity of concentrically-disposed cross-sectionally circular vertical wrought-metal tubes interposed between the upper and lower horizontal tubes and having screw-threaded openings in the upper and lower ends thereof to receive couplings; hollow couplings

screwed into the upper and lower ends of said vertical tubes and having tapered externally-screw-threaded outer ends fitting the tapered screw-threaded openings in the upper and lower horizontal tubes respectively; a grate supported within the circle described by the vertical tubes; a casing surrounding the vertical and horizontal tubes; a steam-dome vertically disposed in the center of the arc described by the vertical tubes; a multiplicity of radially-disposed tubes communicating with the steam-dome and vertical tubes; a water-supply pipe communicating with the lower endless tube; a steam-pipe communicating with the steam-dome; and a grate supported within the circle described by the vertical tubes.

Signed by me at Hartford, Connecticut, this 20th day of March, A. D. 1899.

GEORGE M. DAVIS.
